UNITED STATES PATENT OFFICE.

WESLEY KLINKER, OF UNION MILLS, IOWA.

HAY-STACKER.

SPECIFICATION forming part of Letters Patent No. 314,853, dated March 31, 1885.

Application filed November 28, 1884. (No model.)

To all whom it may concern:

Be it known that I, WESLEY KLINKER, of Union Mills, in the county of Mahaska and State of Iowa, have invented certain new and useful Improvements in Hay-Stackers; and I do hereby declare the following to be a full, clear, and exact description of the invention, such as will enable others skilled in the art to which it pertains to make and use it, reference being had to the accompanying drawings, which form part of this specification.

My invention relates to an improvement in hay-stackers; and it consists in the combination of a suitable frame-work provided with guiding grooves and pulleys for the elevating-ropes to pass over, with the elevator, the hoisting-ropes which are connected thereto, and extending guiding-rails which serve to direct the elevator farther out upon the frame before it is tilted, as will be more fully described hereinafter. This invention is an improvement upon that for which I obtained Letters Patent of the United States, No. 304,270, dated August 26, 1884.

The object of my invention is to provide an apparatus whereby the hay can be raked directly upon the elevator, and thus the hay raised by suitable power to the top of the frame, where it is guided by guide-rails, which are located beneath the grooves, over the top of the stack before it is tilted, whereby the hay will be discharged upon the top of the stack and not fall upon the side thereof, thereby remedying a defect which exists in my former invention above referred to.

In the accompanying drawings, Figure 1 is the side elevation of the hay-stacker embodying my invention. Fig. 2 is a vertical section of the same, showing the rake in a tilted position at the top of the frame.

A represents an inclined frame-work of any suitable description, and which will be of a height proportionate to the stack which is to be built. The rear side of this frame, where the stack is to be formed, is made vertical, while the front side, up which the elevator moves, is made inclined, as shown.

In the inner side of each of the side timbers, B, are made suitable grooves, C, in which the guides of the elevator travel, and which grooves are made curved at their upper ends,

as shown. Upon the outer side of these side timbers at their upper ends are placed the grooved pulleys D, over which the elevating-ropes E pass. Lower down upon the vertical portion of the frame are placed two other pulleys, F, around which the elevating-ropes also pass. To the outer free ends of these ropes the elevating-power is applied. Secured to the frame inside of the side timbers, B, are the inclined guiding-ways G, upon which the elevator rests as it is moving back and forth. Where the curve in the groove C begins near the upper ends of the guide-ways G, I provide metallic guide-extension rails L, which are secured to the side timbers, B, beneath the curved ends of the grooves, and which conform in shape thereto. The extension-rails L project upwardly and rearwardly a little below the outer ends of the grooves and form bearings for the elevator to rest upon as it is being guided in the curved ends of the grooves when near the upward limit of its movement. The elevator consists of the cross-bar H, from which project at right angles to each other the two sets of prongs or teeth I. One of the elevating-ropes is attached to the outer set of teeth or prongs, so that when the elevating-power is applied the first movement of the elevator is to tilt over toward the frame until the inner set of teeth or prongs rest against the inclined guideways. This elevator is always kept in position by means of the two guiding-pins or projections, which project outward from opposite ends of the cross-bar and catch in the guiding-grooves in the inner sides of the timbers B. When this elevator is at the bottom of the frame, the outer set of teeth or prongs rest upon the ground, so that the hay-rake can force all of the hay which has been raked up directly upon it, and thus prevent any necessity of having to handle it.

Any form of rake that may be preferred may be used; but a windrow-rake having the teeth or prongs projecting in the front of it is preferred, for then the rake can be drawn up, so that the prongs or teeth will run in between the prongs or teeth of the elevator. After the hay has been loaded either by a rake or any other suitable means upon the elevator, the elevating-power is applied to the elevating-

ropes, when the elevator tilts backward until its rear set of prongs or fingers strike against the guides. In this position the hay is held, so that it cannot slip off while the elevator is being raised. When the elevator reaches the curved portion of the slot, instead of beginning to tilt over, as was the case in my former invention, and thus partially discharging the hay, the elevator is retained by means of the extension guide-rails L in the position to retain the hay until the extreme outer limit of the curved portions of the slot is reached, when the elevator is tilted suddenly and all of the hay is emptied over the back of the frame directly upon the top of the stack. This construction prevents the hay from being emptied gradually, and thus being discharged partly upon the side of the stack instead of being discharged entirely upon the top thereof.

I claim—
In a hay-stacker, the combination of a frame, A, having the side timbers, B, which are grooved upon their inner sides, suitable guiding-pulleys, inclined guideways which are provided with extension-guides L under the ends 25 of the grooves, an elevator constructed substantially as shown, and elevating-ropes which are secured to the elevator, substantially as set forth.

In testimony whereof I affix my signature in 30 presence of two witnesses.

WESLEY KLINKER.
